[57] CLAIM

The ornamental design for a fork or similar article, as shown and described.

DESCRIPTION

FIG. 1 is a top plan view of a fork or similar article showing my new design;

FIG. 2 is a right side elevational view thereof, the undisclosed side being substantially identical with the side shown herein;

FIG. 3 is a bottom plan view thereof;

FIG. 4 is an end elevational view thereof from the top of FIG. 1;

FIG. 5 is an end elevational view thereof from the bottom of FIG. 3;

FIG. 6 is an enlarged sectional view taken on lines 6—6 of FIG. 1; and

FIG. 7 is an enlarged sectional view taken on line 7—7 of FIG. 1.

FIG. 4

FIG. 1

FIG. 2
